ELECTRIC PARKING METER

Norman A. Whittaker, Seattle, Wash.

Application December 9, 1940, Serial No. 369,223

1 Claim. (Cl. 194—6)

My invention relates to electric parking meters, and more specifically to a device electrically operable by one coin, or by several coins deposited successively, for determining periods of time that motor vehicles are parked along city streets.

Certain objects of the invention are to provide a parking meter of comparatively simple, durable and inexpensive construction, consisting of positive means for indicating the parking time, means for indicating additional parking time, and means for ensuring certainty of electrical operation.

Further objects are to provide means whereby the coins themselves serve as conductors of current in a multiple wiring system for closing circuits by their contact and weight, and also to provide adjustable counter-weight switch means whereby the device is adjustably adapted to be operated by coins of different sizes.

Still further objects are to provide means whereby the coins are slowly brushed along a flexible switch arm under slight pressure so that the wiping or slight abrasion serves to keep the contacting of the switches clean and free from dust or corrosion.

In the drawings:

Figure 1 is a view in side elevation of the parking meter;

Fig. 2 is a view in vertical section taken substantially on a broken line 2—2 of Fig. 1;

Fig. 3 is a view in elevation of the interior mechanism of the device;

Fig. 4 is a top plan view of Fig. 3;

Fig. 5 is a plan view in detail of the main counterbalanced switch arm; and

Fig. 6 is a wiring diagram.

Referring now in detail to the drawings where-in like reference numerals designate like parts in the several views, the numeral 5 indicates a base pedestal upon which is superimposed an upstanding hollow standard 6. A coin receptacle 7 is fixed to the top of said standard, and a mechanism housing 8 is fixed to the top of the coin receptacle. The bottom of the housing projects outwardly from the coin receptacle and serves as a roof for protecting an electric lamp 9 which is fixed thereto as clearly shown in Fig. 1 of the drawings. A coin slot 10 is fixed to the upper exterior portion of the housing 8.

An insulator plate 11, preferably made of glass or other transparent non-conducting material, is fixed to an inside wall of the housing 8 by means of screws 12, and covers the greater portion of said wall. These screws also serve to secure a coin chute, consisting of an inner rail 13 and an outer rail 14, to the insulator plate 11 in spaced apart insulated relation. This chute is in vertical communication with the coin slot 10, as indicated in Fig. 1, and its inner and outer

rails are made of metal and provided with double spaced apart flanges, as most clearly shown in Fig. 4 of the drawings, for the purpose of ensuring contact with coins as more fully herein-after set forth.

The flanges of the outer rail 14 are extended inward at their lower ends, shown at 15, for the purpose of directing coins inwardly while retaining contact therewith. A relatively large disc 16 is fixed to a shaft 17 and its periphery is provided with a plurality of spaced apart pocket slots 18 which are arranged to receive and carry coins from the chute. The shaft 17 extends to a motor 19 which may be fixed to and in spaced relation with the insulator plate 11 by screw bolts 20, and the motor is provided with the usual positive pole 21 and negative pole 22. The motor is conventionally shown in diagrammatic form, and no detail description is deemed necessary except to say that it is preferably of the synchronous type and adapted to rotate at one revolution per hour. A main flexible or resilient switch arm 23 is pivotally connected at 24 to the insulator plate 11, directly below the disc 16, and its proximate reduced end is threadedly adapted to receive a counter-weight 25. A slot 26 extends through this switch-arm for the passage of coins. The remote end of the switch-arm 23 is disposed directly below the coin chute so that it is engaged by coins dropping therefrom, and is also arranged to engage a contact finger 27 which is connected to the insulator plate 11 by a post 28. Another contact finger 29 is connected to the insulator plate at 30 and is also arranged to be engaged by a portion of the main resilient switch arm 23.

In the wiring of the device, a positive lead-in wire 31 is grounded to the inner chute rail 13 at 32 and continues around to a connection with the pivot post 24 of the switch arm 23. A secondary positive wire 33 is grounded at 34 to the outer rail 14 of the coin chute and extends around to a connection with the positive pole 21 of the motor 19. A shunt wire 35 connects the post 28 of the contact finger 27 to the secondary wire 33, and another shunt wire 36 connects the other post 30 of the contact finger 29 to the secondary wire 33. A negative return wire 37 carries the current outward from the negative pole 22 of the motor, and a shunt wire 38, which is connected to this wire 37, extends to the negative pole of the lamp 9, while another shunt wire 39 extends from the positive pole of said lamp to a connection with the positive pole 21 of the motor 19.

In the operation of the device, assuming for example that a coin such as a penny is deposited into the slot 10, this coin, immediately upon contacting the flanges of both the inner and outer rails 13 and 14 respectively of the coin chute,
